UNITED STATES PATENT OFFICE

2,087,153

TREE TAG HOLDER

Serge N. Koulichkov, New York, N. Y., dedicated
to the free use of the people of the United
States

Application October 20, 1936, Serial No. 106,541
2 Claims. (Cl. 224—26)

(Granted under the act of March 3, 1883, as
amended April 30, 1928; 370 O. G. 757)

This application is made under the act of
March 3, 1883, as amended by the act of April 30,
1928, and the invention herein described and
claimed may be manufactured and used by or for
the Government for governmental purposes without
the payment to me of any royalty thereon.

I hereby dedicate the invention herein de-
scribed to the free use of the people of the United
States, to take effect on the granting of a patent
10 to me.

My invention relates to portable holders for
metal tags which are nailed to trees in a forest.

The object of my invention is to provide a con-
venient portable holder or container in which the
15 numbered tags are held in rotation of their suc-
cessive numbers and can be removed one by one,
but always in the order of their numbers.

Another object of my invention is to provide for
metal tags a holder which can be conveniently
20 attached to the operator's belt or to a button on
his coat.

Still another object of my invention is to pro-
vide a holder for tags from which the tags in the
25 correct order of their numbers can be removed
even without looking at them, for instance, in the
dark.

My invention is more fully described in the ac-
companying specification and drawing in which—

Figure 1 is a rear view of my holder;
30 Figure 2 is a side view of the same;
Figure 3 is a sectional view of the same; and,
Figure 4 is a top view of the same.

Similar numerals refer to similar parts
throughout the several views.

35 My holder consists of a housing 1 made of a
metal plate bent over in the middle, the place at
the bend forming the upper side of the housing,
the lower end being rounded off as shown. A
partition 2 is placed between the sides of the
40 housing curved to conform to the curvature of the
edges of the housing plate. Rivets 3 hold the
sides together against the partition. A clip 4 is
formed at the rear side of the housing for remov-
ably fastening the housing to the user's belt. A
45 chain 5 is also provided with a hook 6 and a lock

7 for fastening the housing to a large button on
the user's coat.

A spring wire 8 is fastened by one end in the
upper side of the housing at 9 and is bent to con-
form to the shape of the housing at a distance 5
from the partition 2. The free end of the wire
tends to resiliently spring out of tapering slot 10
in the upper side, a hook 11 being provided for
locking the wire in its place. Metal tags 12 are
assembled on the wire 8 and can be removed one 10
by one by pulling the free end of the wire out of
the slot so as to permit one tag to be removed.

Having thus described my invention, what I
claim for Letters Patent is:

1. In a portable holder for tree tags, the combi- 15
nation of a housing formed of two normally ver-
tical metal plates placed side by side with a clear-
ance between them corresponding to the width of
the tags, the upper portion of the plates being
joined together, a partition wall between the 20
plates at a distance from the edges of the plates,
and a resilient wire for holding the tags, one end
of the wire being fastened in the upper portion
of the housing at one side, the wire extending 25
around within the lower portion of the housing,
the other end of the wire extending through and
above the upper portion of the housing, the upper
portion of the housing at the other side having
a slot for said other end of the wire with a 30
hook for retaining said wire end in locked posi-
tion.

2. In a portable holder for tree tags, the combi- 35
nation of a housing formed of two parallel nor-
mally vertical plates joined in the upper portion,
a separating wall between the plates and inside of
the housing and adapted to keep the plates at a
distance corresponding to the width of the tags,
a wire extending from the upper portion of the 40
housing around said partition to the other side
of the upper portion of the housing, one end of
said wire being fastened, means to releasably
catch the other end, and means to support said
housing on the user's clothing.
